REYNOLD JANNEY, OF NEW YORK, N. Y., AND HARVEY D. WILLIAMS, OF WALLINGFORD, CONNECTICUT, ASSIGNEES TO THE WATERBURY TOOL COMPANY, OF NEW BRITAIN, CONNECTICUT, A CORPORATION OF CONNECTICUT.

FLUID-OPERABLE MECHANISM.

1,172,288.

Specification of Letters Patent. Patented Feb. 22, 1916.

Application filed June 22, 1914. Serial No. 846,619.

To all whom it may concern:

Be it known that we, REYNOLD JANNEY and HARVEY D. WILLIAMS, citizens of the United States, residing at New York and 5 Wallingford, respectively, in the counties of New York and New Haven, States of New York and Connecticut, have invented certain new and useful Improvements in Fluid-Operable Mechanism, of which the 10 following is a specification.

This invention relates to what we will for convenience term "fluid-operable mechanism."

In various arts there are found an oscillatory member and connecting rods jointed to the oscillatory member at opposite sides of the axis of oscillation thereof.

It is the primary purpose of our invention to provide mechanism which is preferably 20 fluid governed in character and is so related with the connecting rods as to operate them and simultaneously automatically compensate for changes in obliquity of said connecting rods.

25 In the drawings accompanying and forming part of the present specification we have shown in detail one of the several convenient forms of embodiment of the invention which to enable those skilled in the art 30 to practise the same will be set forth fully in the following description. We do not, however, restrict ourselves to this particular showing; we may depart therefrom in several respects within the scope of the invention covered by the claims following said 35 description.

Referring to said drawings; Figure 1 is a top plan view of fluid-operable mechanism involving our invention. Fig. 2 is a side 40 elevation of the same. Fig. 3 is a transverse section on the line 3—3 of Fig. 2 looking in the direction of the arrow; Figs. 4 and 5 are perspective views on enlarged scales of a 45 yoke and a piston constituting parts of the mechanism.

Like characters refer to like parts throughout the several figures.

As already noted mechanism involving our invention can be employed in widely 50 different fields; that is to say, the oscillatory member to which we have referred may subserve any desired function. Such an oscillatory member as suits our conditions, is that

denoted in a general way by 2, and it will be assumed that said oscillatory member is 55 a rudder head which after the usual fashion may be rigidly connected with the post 3. Pivoted or otherwise suitably connected with the oscillatory member 2 at opposite sides of its axis of motion are the connecting rods 60 4 and 5, the points of connection of these rods or links 4 and 5 with the oscillatory member 2 being preferably at equal distances from said axis. The two rods are 65 connected at their forward ends as will hereinafter appear, with elements which move in straight paths and these elements form part of a floating fluid-operable mechanism which is of such nature that when either connecting rod is imparted a thrust, a pull of exactly equal extent is given the other by said mechanism.

As shown the rod or link 4 is pivoted as at 6 at its forward end in the slot 7 of the lug 8 projecting laterally from the piston 75 9, the terminal portions of which reciprocate in the duplicate cylinders 10 and 11 mounted for bodily reciprocatory movement in the pillow blocks 12 and 13 rising from the base or bed 14. The two cylinders 80 10 and 11 as shown are connected by the yoke 15 and also by the tie rods or bolts 16 which extend through abutting flanges on the yoke, and cylinders respectively. The lug 8 to which we have referred, extends 85 through the opening 17 of the yoke 15 or the part 15 might be considered as a tube having an opening in one side through which said lug or projection 8 extends. The yoke 15 on the side thereof opposite that 90 having the slot or opening 17 is furnished with an outward projection 18 slotted to receive the forward end of the connecting rod 5 pivoted to said projection 18 as by the pivot 19. The reciprocatory mounting of 95 the two cylinders and piston with the rods connected with the cylinder and piston mechanisms respectively compensates for variations in obliquity of the two connecting rods or links as they are oscillated and 100 not only is this so but the pull applied to either rod exactly equals the thrust exerted on the other. The two projections and lugs 8 and 18 have a bearing upon the base or bed 14, the latter having parallel ways or 105 ribs 20 flat on their upper sides to receive

the correspondingly flattened surfaces on the under side of the two lugs or projections 8 and 18. The piston 9 also has a bearing engagement against the connecting yoke 15, 5 the two parts having flat engaging surfaces 21 for such purpose. It, therefore, follows that as the two coaxial cylinders and the piston move backward and forward, there is no possibility of their turning. This, of 10 course, is merely one of several advantageous ways of preventing rocking or movement of the two cylinders and their coöperative piston about their longitudinal axes.

The power for reciprocating the piston 15. 9 may be supplied in any desirable manner, for instance by the hydraulic variable pump 22 which may be constructed exactly like the pump or so-called "A-end" of the variable speed gear shown in Letters Patent No. 20 924,787 granted to Reynold Janney, June 15, 1909, and to which reference may be had. This pump 22 and its operating motor as 25 may be mounted in any desirable manner. As shown the pump and its motor of "electric" type, are both rigidly mounted on the yoke 15, but this as will be inferred, is not a matter of necessity. After the usual fashion the electric motor 23 is coupled to the shaft of the hydraulic pump 22, the latter being provided with a regulator such as the well-known "tilting box" operable by the shaft 24 which can be actuated directly by hand, by power or otherwise. From the 30 pump the pipes 25 and 26 extend, the pipe 35 25 being connected with the cylinder 10, while the pipe 26 is connected with the cylinder 11. The two pipes are intersected by a safety valve 27 of ordinary kind and which also acts as a by-pass after the usual 40 fashion. Through the operation of the control shaft 24, fluid can be directed in alternation into the cylinders 11 and 12 so as to effect the relative operation of the piston 9 and connected cylinders 10 and 11 and thereby apply a thrust to one of the two 45 connecting rods 4 and 5 and a pull on the other in accordance with the cylinders 10 and 11 into which the liquid is initially pumped by the pump 22.

50 What we claim is:

1. The combination of piston mechanism and cylinder mechanism both mounted for relative reciprocatory movement, an oscillatory member, rods connected with the oscillatory member at opposite sides of its center of motion, one rod being connected with the piston mechanism and the other with the cylinder mechanism, and means for relatively operating the piston and cylinder mechanisms.

2. The combination of piston mechanism and cylinder mechanism both mounted for relative reciprocatory movement, an oscillatory member, rods connected with the oscillatory member at opposite sides of the

center of motion, one rod being connected with the piston mechanism and the other with the cylinder mechanism, means for relatively operating the piston and cylinder mechanisms, and means for positively preventing the piston mechanism and cylinder mechanism from rocking. 70

3. The combination of a pair of coaxial cylinders, a connecting device rigidly connecting the cylinders, a piston, the terminals 75 of which are reciprocatory in the said cylinders, an oscillatory member, rods connected with the oscillatory member at opposite sides of its center of motion, one rod being connected with the piston and the other with 80 said connecting device, and means for relatively reciprocating the piston and the cylinders.

4. The combination of piston mechanism and cylinder mechanism, both mounted for 85 relative reciprocatory movement, an oscillatory member, rods connected with the oscillatory member at opposite sides of its center of motion, one rod being connected with the piston mechanism and the other 90 with the cylinder mechanism, and a hydraulic variable pump for relatively operating the piston and cylinder mechanisms.

5. The combination of piston mechanism and cylinder mechanism, an oscillatory 95 member, rods connected with the oscillatory member at opposite sides of the center of motion, one rod being connected with the piston mechanism and the other with the cylinder mechanism, and means for relatively operating the piston and the cylinder 100 mechanisms.

6. The combination of coaxial cylinders, means for supporting the cylinders for reciprocating movement, a yoke between and 105 rigidly connected with the cylinders, a piston, the terminals of which are located in the cylinders for reciprocation therein, said piston being inclosed by the yoke and having a lug extending outwardly from the 110 yoke, the yoke also having a companion lug, an oscillatory member, rods connected with the oscillatory member at opposite sides of its center of movement and with said lugs, and a hydraulic variable pump for relatively reciprocating the piston and the cylinders. 115

7. The combination of coaxial cylinders, means for supporting the cylinders for reciprocating movement, a yoke between and 120 rigidly connected with the cylinders, a piston, the terminals of which are located in the cylinders for reciprocation therein, said piston being inclosed by the yoke and having a lug extending outwardly from the 125 yoke, the yoke also having a companion lug, an oscillatory member, rods connected with the oscillatory member at opposite sides of its center of movement and with said lugs, a hydraulic pump for relatively reciprocating 130

ing the piston and the cylinders, and a motor for operating the pump, both the pump and the motor being mounted on said yoke.

8. The combination of a pair of coaxial cylinders, a yoke rigidly connecting the same, a piston in the yoke, both the yoke and the piston having a bearing on the framework of the machine and the piston having a bearing engagement with the yoke 5 to thereby prevent rocking of the piston and the cylinders as they reciprocate, an oscillatory member, and connecting rods con-

nected with the oscillatory member at opposite sides of its center of movement, one of the connecting rods being connected with 15 the piston and the other with the yoke.

In testimony whereof we affix our signatures in presence of two witnesses.
